UNITED STATES PATENT OFFICE.

CHRISTIAN WILLIAM MEINECKE, OF JERSEY CITY, NEW JERSEY, ASSIGNOR
TO MEINECKE & CO., OF NEW YORK, N. Y., A CORPORATION OF NEW
JERSEY.

DESIGN FOR AN ICE OR HOT-WATER BAG.

SPECIFICATION forming part of Design No. 35,815, dated November 26, 1901.

Application filed August 24, 1901. Serial No. 73,206. Term of patent 14 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for Ice or Hot-Water Bags, of which the following is a specification.

This design consists in an ice or water bag of circular outline, with radiating lines and having perforated lugs or projections located diametrically opposite one another, with the outer edges of the bag between said lugs free from obstruction. These oppositely-located perforated lugs, in combination with the radiating lines on a bag of circular outline, the said bag having the edges thereof between said lugs free from obstruction, are the distinguishing features of the design.

The design is illustrated in the annexed drawings, in which—

Figure 1 is a perspective view of the bag. Fig. 2 is a plan view of Fig. 1.

The bag *a* is of circular or approximately circular—say polygonal—outline, with radiating lines or creases *b*. The perforated lugs or projections *h* form eyes situated diametrically opposite one another, and the outer side edges of the bag, between the lugs or projections *h*, are free from obstruction. These projections are each shown at a flat or uncreased part of the circumference or outside of the bag.

The design gives a striking, characteristic, and distinguished appearance.

What I claim as new, and desire to secure by Letters Patent, is—

The design for an ice or water bag as herein shown and described.

In testimony whereof I have hereunto set my hand in the presence of two subscribing witnesses.

CHRISTIAN WILLIAM MEINECKE.
